PAPER SLITTING AND WINDING MACHINE

Application filed December 14, 1925. Serial No. 75,419.

This invention relates to improvements in paper slitting machines, and more particularly to the provision of web supporting means, such as a slitter board, movable toward and away from the slitter or slitters whereby the web while travelling may be either engaged with the slitters or supported in a position removed therefrom, of means, such as guides on said slitter-board, for preventing displacement of the web transversely of the machine, and of a movable slitter-guard such as to prevent contact of the hands of the operator and of the web with the cutter or cutters at times when web is removed from its position for engagement with the cutters. These and other objects accomplished by the invention will be more fully understood from the detailed description and drawings which follow.

Improvements herein disclosed in respect to the winding mechanism are claimed in a divisional application filed May 2, 1927, Serial No. 188,325.

In the drawings forming part of the present disclosure:—

Fig. 1 is a side elevation of a machine embodying the invention;

Fig. 2 is an end view thereof, partly in section, looking from the right of Fig. 1, certain parts of the machine being omitted for the purposes of clearer illustration;

Fig. 3 is a top plan view of slitter-board controlling devices;

Fig. 4 is a side elevation, with parts broken away, of a winder bar supporting arm and associated mechanism;

Fig. 5 is an elevation of the upper end of the winder bar supporting arm as viewed from the left of Fig. 4;

Fig. 6 is an elevation of the winder bar supporting arm, looking from the right of Fig. 4;

Fig. 7 is a side elevation of the device shown in Fig. 3;

Fig. 8 is an enlarged vertical sectional view on the line 8—8 of Fig. 2, showing slitting and spreader bar mechanism;

Fig. 9 is a top plan view of a slitter blade and guard therefor;

Fig. 10 is an enlarged vertical sectional view on the line 10—10 of Fig. 8; and

Fig. 11 is a side elevation of a stop device for supporting the slitter guard when the slitter-board is in an inoperative position.

Referring to the drawings, wherein like reference characters indicate like parts throughout the several views, 5 represents the last roll of a paper drier, 6 the drier belt which passes over said roller, and 7 a roller under which the belt passes as it travels through the drier. A web 8 of crepe paper or other material, after passing through the drier, is directed by a guard 9 into the slitting and winding machine, said guard being mounted on the frame piece 10 of the machine which also serves as a support for the slitting mechanism.

The slitting mechanism, together with the winding mechanism presently to be described, may be driven from any desired source of power by any suitable means (not shown), and said slitting mechanism (Figs. 1 and 8 to 11) preferably comprises a shaft 11 journaled in suitable bearings on the machine framework and having rigidly secured thereto at desired intervals a plurality of circular slitters, one of which is indicated at 12. These slitters are positioned on shaft 11 between collars 12', 12' and serve to cut web 8 into a plurality of narrower webs 8', 8", and for this purpose the web 8 is passed under a roller 13 journaled on frame piece 10 and then between the slitters and a slitter-board 14. Said board is pivotally mounted on the machine so that, before the same is started, the board may be turned downwardly from the slitters to the position shown in dotted lines, Fig. 8, to permit the web to be freely passed to and secured on the winding mechanism by an attendant.

Referring to Figs. 1, 7 and 8, the slitter-board 14 is mounted between spaced clamps 15, 15, rigidly secured on a shaft 16, each end of which is journaled in a suitable bearing on an arm 16' of a pedestal 16" which constitutes a part of the machine framework. Suitable fastening means may be employed to hold the clamps securely in engagement with the board as for example bolts which extend

through the clamps and board, one of said bolts being indicated at 17. A handle 18 is rigidly secured as by a key 19 on a projecting end of shaft 16, and when the handle is moved in a counter-clockwise direction the board may be turned to a vertical position, thereby lifting the web 8 into engagement with the slitter blades 12. The slitter board is maintained in operative relation with the slitters by a stop pin 20 secured in an extension 21 of pedestal arm 16' and by a pawl 22 pivotally mounted at 23 in said extension. As shown in Fig. 7, stop pin 20 is engaged by a shoulder 24 of a collar 25 rigidly secured on shaft 16, the shoulder and pin preventing further movement of the board to the left after it reaches the full line position of Fig. 7. The pawl 22 engages a shoulder 26 of collar 25 and locks the board in its operative position. One end of a spring 27 is engaged over a lug 28 formed on the left end of pawl 22, the opposite extremity of said spring bearing against a lipped bracket 29 secured by a bolt 30 to the pedestal arm 16'. By depressing the pawl against the tension of spring 27, the slitter-board can be turned to the right through the medium of handle 18, thereby moving the board and web 8 out of contact with the slitters. The shoulder 26 then engages pin 20 which thus serves as a stop for the board in its inoperative position. The slitters are provided with a guard (Figs. 8 to 11) consisting of a guard plate 31 for each slitter blade 12, said plate having an elongated slot 32 through which the slitter blade normally projects. The plates 31 are supported on strips 33, 33 suitably secured as by rivets 34, 34 to L-bars 35, 35 which constitute part of the slitter guard frame. Spacing pieces 36, 36 are interposed between said strips and the L-bars, and the ends of each plate 31 are engaged under L-bars 35, 35 and secured between the latter and strips 33, 33 by brackets 37, 37 riveted at 38, 38 to the plate 31 and having set-screws 39, 39 which may be turned down into engagement with the horizontal flanges of L-bars 35, 35. The slitter guard frame further includes an L-bar 40 at each end thereof, and said frame is pivotally mounted at 41 on a bracket 42 secured to a cross-strut 43, preferably made of wood and constituting part of the machine framework. The pivotal connection for the slitter guard frame with cross-strut 43 further includes strap hinges, one of which is indicated at 44 (Fig. 8), the same being riveted at 45, 45 to the under side of L-bar 40.

The head 46 of a bolt 47 serves as a stop for the slitter guard when the slitter bar is turned to its inoperative position indicated by dotted lines in Fig. 8. Said bolt passes through a suitable aperture in the slitter guard frame and is secured by nuts 48 and 49 in a bracketed extension 50 of the machine

framework. It will thus appear that when the slitter-board is returned to its inoperative position, the slitter guard will drop to a position removed from or below the edges of the slitter blades and into engagement with the head 46 of bolt 47. The web 8 can then be passed by an attendant into the machine without danger of his hands or the web coming into contact with the slitters. When the slitter-board is turned up to lift the web into contact with the slitter blade, said board raises the slitter guard to the full line position of Fig. 8 and supports the same in such position while the web is being slit into the plurality of narrower webs 8', 8'. Sidewise movement or displacement of the web with respect to the slitter-board is prevented by a guide 51 at each end of the board, said guides being secured to the board by any suitable fastening means such as a bolt 52 and nuts 53, 54. The guides 51 have curved upper edges which engage the under side of the guard beneath the L-bars 40, 40 at opposite sides thereof, as shown in Fig. 11, and the guard is supported on said curved edges of the guides and raised and lowered thereby when the slitter board 14 is raised to the full line position shown in Fig. 8, or lowered to the dotted line position shown in said figure.

According to the present invention, suitable means are employed for spreading the web or webs of material vertically as the same pass from the slitting mechanism to the winding mechanism. Said spreading means preferably comprises a plurality of spreader bars 55, 55, one for each of the several webs 8', 8' (Figs. 2 and 8). Each bar 55 is provided longitudinally thereof with a suitable groove receiving a strip 56 of steel or other material which contacts with the adjacent web 8', and centrally of the bar is a suitable opening which receives the head 57 and squared shank 58 of a spreader bar operating shaft the upper end of which is screw-threaded as indicated at 59. The squared shank 58 passes through an opening of like configuration in a flanged collar 60 secured by screws 61, 61 to the cross-strut 43. It will thus appear that, while the spreader bar and its operating shaft may be moved vertically, the same are prevented from rotating by reason of the squared fit between the shank 58 and the collar 60. The spreader bar operating shafts extend vertically through suitable spaced openings of the cross-strut 43, the threaded part 59 of each shaft extending through an opening in a flanged collar 62 secured to the cross-strut as by screws 63, 63. Each spreader bar operating shaft is provided with a hand-wheel 64 threaded thereon and by means of which the bar can be raised and lowered through the turning movement of said wheel. It will thus appear that the several spreader bars can be moved vertically to different positions with respect to each other 130

and that the several webs 8', 8" will be separated or spread apart vertically from the point at which web 8 is slit to the mechanism on which the webs 8', 8" are wound. Spreading of the webs in the manner indicated prevents interference between the webs and interlocking of the ends of individual rolls wound therefrom to form a large roll 70 in a manner to be presently described.

The winding mechanism of the present invention (Figs. 1, 2 and 4 to 6) includes a winder bar 65 which is introduced into the machine on one side thereof through the medium of a carriage 66. Said carriage is arranged for movement transversely of the machine along a track 67, and for this purpose the carriage is provided with a grooved roller 68 which engages the track and is prevented from displacement by a guard 69. In order to start roll 70, the slitter-board 14 is turned down and web 8 is passed by an attendant through the machine over a winding drum 71, rotating in the direction of the arrow (Fig. 1). The winder bar is then dropped from its carriage into supporting means adjacent the drum so that the winder bar rests on the web and drum. The free end of the web is then turned onto the winder bar and the roll started by rotation of the drum 71. Passing of the web can be performed while the machine is in operation and after the roll 70 is started the slitter-board is raised, thereby lifting the web into contact with cutters 12 which sever web 8 into webs 8', 8". The spreader bars are then lowered into engagement with webs 8', 8" at different positions so that the webs will be spread as above described. The roll 70 is thus constituted by a plurality of individual smaller rolls wound in end to end relation on bar 65.

Drum 71 is mounted on a shaft 72, each end of which is journaled in a suitable bearing 73, secured to a frame piece 74 of the machine. The means for supporting the winding bar 65 in operative relation with drum 71 preferably comprises swinging supporting arms disposed one at each side of the machine and arranged for movement so that the roll 70 and its contained winder bar may be caused to travel over the surface of winding drum 71 between the full and dotted line positions of the roll indicated respectively at A and C (Fig. 1). Said arms are provided with suitable mechanism for moving the same in the manner above indicated and are further equipped with devices which automatically grip and release the winder bar. Since the construction of the winder bar supporting arms, the means for moving the same, and the associated gripping and releasing devices are identical at both sides of the machine, it is only necessary to describe the mechanism located adjacent one side thereof. Each arm 75 includes a large split collar 76 at the lower part thereof, a bifurcated upper extremity

providing jaw portions 77, 77, and a segmental gear 78 formed in or secured to a web-like part of the arm. The arm 75 is rigidly secured on shaft 72 adjacent one extremity thereof through the medium of collar 76 and set-screws threaded into suitable bosses on the split collar sections. One of these set-screws and the corresponding bosses are indicated respectively at 79 and 79', 79" in Fig. 4. The segmental gear 78 engages a pinion 80 rigidly secured on a shaft 81 extending transversely of the machine and journaled in suitable bearings, one of which is indicated at 82. Bearing 82 is formed on arm 16' and the shaft 81 projects outwardly through said bearing and has secured thereon a ratchet 83 and a hand-wheel 84. The hand-wheel serves to rotate the shaft 81 which, through the medium of pinion 80 and segmental gear 78 rotates the arm 75 so that roll 70 may be moved over the surface of drum 71 as above described. A pawl 85, pivoted at 86 on the bearing 82, serves to prevent backward movement of the arm 75 and the roll 70 when the two are being moved, for example, from the initial winding position A to the intermediate and final positions indicated respectively at B and C. Said pawl is manually released to permit movement of the arm from position B to position A in order to start a new roll.

At each end the winder bar 65 has portions 87 and 88 of relatively different diameters, and when the winder bar is dropped into its supporting arms 75 between jaw portions 77, 77, portion 87 initially rests on the bottom 89 of the jaw provided by portions 77, 77. A lever 90 is pivoted at 91 in an offset portion or boss 92 formed on one of the jaw portions 77, 77 and said lever is provided with a pawl 93. When the winder bar is dropped into place as above described, the extention 88 trips lever 90 thereby disengaging the pawl from a ratchet 94 located at one side of the jaw 77, 77 and secured as by a key 95 on a shaft 96 journaled in a suitable bearing in boss 92. A lever 97 is rigidly secured to said shaft at the opposite side of the jaw and when lever 90 is tripped and pawl 93 disengaged from ratchet 94, lever 97 is thrown from a substantially vertical position into engagement with extension 87 of the winder bar through the medium of a coiled spring 98, one end of which is engaged in a suitable aperture 99 formed in an offset portion 100 of lever 97. The opposite extremity of spring 98 is engaged in the apertured end of a bolt 101 threaded into a boss 102 formed on one of the sections of split collar 76, said bolt serving to adjust the tension of spring 98 and being secured in its adjusted position by means of a nut 103.

The tension of spring 98 on lever 97 produces a pressure of the latter on the winder bar, which tension and pressure serve, particularly at the time winding of roll 70 is

started, to produce a uniform hard roll. As the roll 70 builds up at position A the winder bar 65 gradually moves away from the surface of roll 71 and raises lever 97 against the tension of spring 98 thereby moving ratchet 94 in a counter-clockwise direction past pawl 93. When the winder bar moves out of jaw portions 77, 77, a clip spring 104 secured at 105, 105 to one of said portions, maintains pawl 93 in engagement with ratchet 94 so that the tension of spring 98 cannot move lever 97 back past jaw portions 77, 77 until another winder bar is inserted therebetween and engaged with lever 90, at which time the latter will again be tripped so that the above described operations may be repeated at position A.

When the roll 70 has been built up to a diameter of say approximately six inches the same is moved from position A to position B and then to position C by means of the supporting arm operating mechanism above described. Previous to the arrival of roll 70 at position C, a hinged section 106 of a vertical guide 107 is lifted to the dotted line position shown in Fig. 1, where guide section 106 may be supported by engaging a hook 108 with a pin 109 suitably secured on said section adjacent the free extremity thereof. The lower part of guide 107 being opened, the end of the winder bar is received in said guide, the roll 70 then resting on winding drum 71 and an auxiliary fluted winding drum 110 rotated by any suitable means (not shown) at a surface speed corresponding to that of drum 71. Hook 108 is then disengaged from guide section 106 and the latter allowed to drop downwardly to the full line position shown in Fig. 1, the guide section 106 being maintained in its closed position by a detent 111 which engages pin 109. The auxiliary winding drum 110 is mounted on a shaft 112, the end of which is journaled in a suitable bearing 113 mounted on a pedestal 114 constituting part of the machine framework. The pedestal 114 also serves as a support for a vertical frame piece 115 on which the frame piece 10 is bolted or otherwise suitably secured.

Rotation of roll 70 by drums 71 and 110 builds said roll up to the desired size, indicated for example by the large dotted circle at the left of Fig. 1, and causes the winder bar to lift or move lever 97 to one side of the jaws 77, 77 of the winder bar supporting arm where, after the winder bar has passed out of the jaws, said lever is retained and prevented from snapping back past said jaws by the pawl 93 and ratchet 94. The winder bar supporting arm is then returned to position A by rotating hand-wheel 84 and an empty winder bar passed into the machine, through the medium of carriage 66, for association with the winder bar supporting arm and the starting of a new roll.

The winder bar contained within the roll

winding at position C, gradually rises within guide 107 which serves to maintain said roll in proper position with respect to drums 71 and 110. When said roll reaches the desired size, the slitter-board is lowered and the spreader bars raised. The web is then severed from the roll between the slitting and winding mechanisms so as to leave a free end extending over winding drum 71. The empty winding bar is then dropped onto the web and drum and the bar engaged with the supporting arms as previously described. The free end of the web is then passed around said bar to start the new roll. The winding operation again proceeds at position A and the slitter-board is raised and the spreader bars lowered so that the web forming the new roll is severed and the portions thereof spread vertically as the material is being wound on the second bar. The finished rolls can be removed from the machine in any desired manner, as by lifting or rolling the same out of the machine manually, or through the medium of any suitable mechanism adapted to accomplish this purpose.

What is claimed is:

1. In a machine of the character described, the combination of a slitter, a web supporting device movable away from the slitter whereby the web while traveling past the slitter may be engaged with the slitter or supported in a position removed therefrom, and means on said device for preventing a displacement of the web transversely of the machine.
2. In a machine of the character described, the combination of a web slitter, a slitter board pivotally mounted adjacent the slitter and adapted to support the web, means for turning the board toward and away from the slitter whereby the web may be engaged with said slitter or supported in a position removed therefrom, a spring controlled detent for locking the board against movement while the web is engaged with the slitter, and a stop for limiting the movement of the web supporting device away from the slitter and for supporting said device when engaged therewith.
3. In a machine of the character described, the combination of a slitter, web supporting means movable toward and away from the slitter whereby the web may be engaged with said slitter or supported in a position removed therefrom, and a guard extending between said means and the slitter.
4. In a machine of the character described, the combination of a slitter, web supporting means movable toward and away from the slitter whereby the web may be engaged with said slitter or supported in a position removed therefrom, and a pivotally mounted guard extending between said means and the slitter and provided with an opening through which the slitter is adapted to project.

5. In a machine of the character described, the combination of a slitter, a web-supporting device movable toward and away from the slitter whereby said web may be engaged with the slitter or supported in a position removed therefrom, and a movable slitter guard controlled by the movement of said web-supporting device.

6. In a machine of the character described, the combination of a web slitter, a movable slitter guard having an opening through which said slitter is adapted to project, and a movable web-supporting device adapted on movement in one direction to swing the guard past the slitter and present the latter to the web through said opening.

7. In a machine of the character described, the combination of a web slitter, a slitter guard movable inwardly and outwardly past the cutting edge of said slitter, and means for supporting the free end of the guard when the same has been moved outwardly past said cutting edge.

In testimony whereof I have signed this specification.

GEORGE LAMOUREUX.
